L. KINNEY.
MECHANICAL MOVEMENT EXERCISER.
APPLICATION FILED DEC. 17, 1917.

1,283,210.

Patented Oct. 29, 1918.

UNITED STATES PATENT OFFICE.

ISRAEL KINNEY, OF LOS ANGELES, CALIFORNIA, ASSIGNOR TO SAMUEL D. MACKINNON.

MECHANICAL-MOVEMENT EXERCISER.

1,283,210.

Specification of Letters Patent. Patented Oct. 29, 1918.

Application filed December 17, 1917. Serial No. 207,439.

To all whom it may concern:

Be it known that I, ISRAEL KINNEY, a citizen of the Dominion of Canada, residing at Los Angeles, in the county of Los Angeles 5 and State of California, have invented new and useful Improvements in Mechanical-Movement Exercisers, of which the following is a specification.

This invention relates to a mechanical 10 movement especially adapted for use in exercising the body and as an amusement device.

The objects of this invention are first, to provide a device which requires the use of 15 the body muscles to operate the same; second, to provide a device which will disturb and roll the internal organs of the torso; and third, to provide a device which will shake and vibrate the body.

20 In addition to the broader objects of this invention there are further objects, which include providing a device which may serve as an amusement, will be simple, cheap, and durable in construction.

25 I accomplish these objects by means of the embodiments of my invention illustrated in the accompanying drawing, in which;

Figure 1, is a side view of a preferred form of my device, a portion being broken 30 away to better show the means for adjusting the reclining back. Fig. 2, is a top view of the structure shown in Fig. 1. Fig. 3, is a modified form. Fig. 4, is another modified form. Fig. 5, is an enlarged section through 35 a block or knob.

Referring more particularly to Figs. 1 and 2, 6 is a base or table of circular form. Secured to the center of the base 6 upon the under side thereof is a pivot leg 7. The 40 height of leg 7 may be adjusted by means of the screw connection between it and the base. The end of pivot leg 7 is rounded and has a screw which extends through a plate 9 with the head of the screw below the plate 45 and the rounded end of the pivot leg resting on the plate, thereby providing for a rolling motion of the pivot leg. The plate 9 is fastened by any suitable means to a foot, which rests upon the floor, thus preserving 50 the floor or carpet from injury. If desired the rounded end of the pivot leg may rest directly upon the floor, no plate being used. In either construction a universal movement 55 between the leg and floor is provided. The under side of base 6 is provided with projections 10 in the form of blocks or knobs

fixed thereto adjacent the periphery, whereby rolling the point of contact at the periphery will cause vibration of the base 6. The blocks may be arranged in oval form so 60 that in certain positions the effort required to operate the exerciser is greater than in others.

The structure shown in Figs. 1 and 2 is intended to be used by the patient either lying upon his back or reclining thereon in a sitting posture. A seat 11, is supported above the base 6 by means of side pieces one 65 of which is indicated in Fig. 1 by 12. These side pieces are fastened to posts 13, which 70 are mortised to the base. Pivoted to the seat 11 is an adjustable back 14. In order to fix the back 14 in any position of adjustment, a segment having a rack 15 thereon is pivoted to the under side of the back. The rack 15 is 75 arranged to engage a catch bar 16. This is a common type of adjustment and needs no further description.

The edges of the seat are provided with raised portions 17 and 18, serving as hand 80 grips, by which the patient may steady himself. The base 6 is provided with a raised portion 19 at the edge, which serves as a foot rail and rest for the feet, when it is not desired to place the same on the floor. 85

The structure shown in Figs. 1 and 2 is operated in the following manner: The patient sits upon the seat 11 with his feet resting upon the floor and his back resting upon the back 14, which has been adjusted to the 90 desired angle. He now rolls the base by pressing upon the floor with one foot then with the other, so that the point of support rolls or progressively moves from one 95 block to another. The movement of the base 6 causes a like movement of the body with a consequent rolling of the internal organs within the cavity of the body. At the same time the abdominal muscles are exercised by the effort made to operate the device. As 100 the point of contact is transferred from one block to another there is a knocking or shaking causing a vibration which is transmitted to the body, thereby gently jarring or shaking up the entire body. This induces 105 ready perspiration and promotes freedom of the bowels.

The structure may be used by placing the feet upon the base with the heels behind the rest 19, and then moving the center of gravity of the body so as to cause a rolling of the exerciser. By using the exerciser in 110

this manner more of the body muscles are called into play and the results attained are varied.

Referring particularly to Fig. 3, a rocking chair type of structure is shown. This is especially suitable for persons who are very feeble or those who desire to use the structure merely for the pleasant rolling sensation. The upper part of the device is of the ordinary arm chair type. A rocking rim 21 is fixed to the bottom of the legs and need be only about two thirds of a circle. Secured to cross pieces 22 is a pivot leg 23 having a foot 24. This structure has no shaking or vibrating knobs upon the rocker, but these may be added, if desired. The method of operating the same is obvious.

In Fig. 4, I have shown a stool having a seat 25 and an arm 26. A number of legs 27 serve as the base and knockers. A block 28 is disposed between the legs, and they are fastened thereto. A central pivot leg 29 is secured to block 28 by a screw connection, so that the center leg may be moved into a position free of the floor and the stool rest upon its legs in the usual manner. Center leg 29 is connected to a foot by a universal connection, and the foot should be fastened to the floor to prevent the stool from tipping over. In all cases where the device is very much elevated, it will be necessary to fasten the foot to the floor to prevent tipping.

The blocks 10 of Figs. 1 and 2 may be equipped with stiff springs or rubber cushions, which make the operation silent and also act to speed the movement. Such a construction is shown in Fig. 5. The block 30 is equipped with a tenon 31 adapted to fit in a mortise in the base. The contact face of the block is inclined, so it will not mar or injure the floor or carpet. A bore is formed in the face, and a rubber cushion 32 is placed therein.

It is also evident that my construction may be embodied in a rocking horse suitable for children. Various other modifications of the structure may be used to suit the device to the particular circumstances without departing from my invention.

What I claim is:

1. In a device of the class described, a base having supports arranged so that it may be tilted in all directions, said supports being arranged in spaced relation, whereby a wabbling shaking movement may be obtained.

2. In a device of the class described a wabbling base having a pivot projecting

from its center, said base having a series of elevations and depressions on its under side forming contacts, whereby wabbling movement of said base will produce vibration.

3. In a device of the class described adapted to rest upon a surface, a wabbling base comprising a series of points of support, upon which it is adapted to progressively rest, and a pivot leg fixed with respect to said base so that the latter is always supported thereon, said pivot leg having a universal movement with respect to said surface, whereby wabbling movement of said base will produce vibration.

4. In a device of the class described, a wabbling base, means to jolt said base during its wabbling movement, and a rest for the body to recline upon mounted upon said base, said rest having a portion disposing the body so that the internal organs of the user will gravitate in the abdominal cavity, 75 rolling thereabout.

5. In a device of the class described, a base having supports arranged so that it may be tilted in all directions, said supports being arranged in spaced relation, whereby 85 a wabbling shaking movement may be obtained, and a rest for the body to recline upon mounted upon said base, said rest having a portion disposing the body so that the internal organs of the user will gravitate in 90 the abdominal cavity, rolling thereabout.

6. In a device of the class described a wabbling base having a pivot projecting from its center, said base having a series of elevations and depressions on its under side 95 forming contacts whereby wabbling movement of said base will produce vibration, and a rest for the body to recline upon mounted upon said base, said rest having a portion disposing the body so that the internal organs of the user will gravitate in the 100 abdominal cavity, rolling thereabout.

7. In a device of the class described adapted to rest upon a surface, a wabbling base comprising a series of points of support, upon which it is adapted to progressively rest, and a pivot leg fixed with respect to said base so that the latter is always supported thereon, said pivot leg having a universal movement with respect to said surface 110 whereby wabbling movement of said base will produce vibration, and a rest for the body to recline upon mounted upon said base, said rest having a portion disposing the body so that the internal organs of the 115 user will gravitate in the abdominal cavity, rolling thereabout.

ISRAEL KINNEY.
